UNITED STATES PATENT OFFICE.

ALLEN E. OSTRANDER, OF NEW YORK, N. Y., ASSIGNOR TO AMERICAN CAR AND FOUNDRY COMPANY, OF ST. LOUIS, MISSOURI, A CORPORATION OF NEW JERSEY.

CAR-END FRAMING.

No. 909,208.

Specification of Letters Patent.

Patented Jan. 12, 1909.

Application filed July 26, 1908. Serial No. 445,367.

To all whom it may concern:

Be it known that I, ALLEN E. OSTRANDER, residing at New York city, county, and State, and being a citizen of the United States, have invented certain new and useful Improvements in Car-End Framing, of which the following is a full, clear, and exact description, such as will enable others skilled in the art to which it appertains to make and to 10 use the same, reference being had to the accompanying drawings, which illustrate the preferred form of the invention, though it is to be understood that the invention is not limited to the exact details of construction 15 shown and described, as it is obvious that various modifications thereof will occur to persons skilled in the art.

In said drawings: Figure 1 is a perspective view of one of the end post pockets. Fig. 2 is a transverse sectional view of a car equipped with my improved end framing. Fig. 3 is a plan view of the parts of the under-frame and appurtenances shown in Fig. 2. Fig. 4 is a sectional view, the section being 25 taken on line 4—4 of Fig. 2. Fig. 5 is a side elevational view of a fragmentary portion showing the corner post pocket in position.

The object of the invention is to produce an end framing particularly well adapted to 30 resist end thrusts caused by shifting of the load within the car and incidental to this the pockets for the end posts are secured in position with the major portion thereof below the upper plane of the end sill with said 35 end sill serving preferably as one of the walls of said pockets when in position so as to permit placing the end posts and the end furring strips next the end sills in which event the end sheathing will extend vertically 40 above the end sill. As the end furring rises to a plane above the upper plane of the end sill and the end sheathing is secured to said furring a weather proof lower end construction will result.

Owing to the end posts, end braces and corner posts extending below the upper plane 45 of the end sill and the end furring resting on the end post pockets and longitudinal sills, short sections of end furring may be used as 50 nailing strips for the end sheathing and the car flooring, said furring being provided with a shouldered portion on which the trans-

versely extending end board of said flooring will rest. Secured in position outside of the side sills and back of the end sill are corner 55 post pockets adapted to receive the corner posts and framing rods.

Referring particularly to the parts, A indicates a central girder or center sills; B side sills; C an end sill, all of which are shown as 60 channel members which may be either rolled or pressed as may be desired, although I do not wish to be limited to channel shaped sill members as it is evident that any suitably shaped sills may be combined with the end 65 framing hereinafter more fully described.

Between the center sills at each end thereof are pressed members 2 which are provided with downwardly extending flanges 3 for riveting to said center sills and an end flange 70 4 for connection with the end sill. At each side of the center sills are end post pockets 5 shown in detail in Fig. 1. Said pockets comprise vertical flange 6, through which rivets are driven for connection to the end sill, and 75 laterally projecting flanges 7 upon which rest the end furring strips 8 which strips are secured in position by means of bolts 9 passing through openings 10 in the flanges 7 and through said furring strips, as shown in 80 Fig. 2.

The end post pockets comprise rear walls 11, side walls 12 and an intermediate filler 13 which latter is perforated for the passage therethrough of the end framing rods 14, and 85 when the pockets 5 are secured in position the end sill C serves as a closure for the end post pocket 15 and end brace pocket 16 as shown in Fig. 3.

Connected to the side sills B and end sill C 90 are corner post pockets 17 which are provided with laterally extending flanges 18 on which rest the side nailing strips 19 and with vertical flanges 20 and 21 respectively for connection with said side sills and end sill as 95 best shown in Fig. 5.

It will be observed that the corner post pockets are placed outside or beyond the side sills and in such position that the side sills serve as closures forming the inner walls of 100 said corner post pockets whereby the side posts will rest in position next the side sills.

Resting upon the flanges of the center sills and carried thereby, or by the pressing 2 in-

terposed between said sills, is a short section 22 of furring which is secured by bolts 23 extending therethrough and through said pressing, said furring extending relatively to 5 the inner faces of the end post pockets. The furring strips 8 rest upon the flanges 7 of the end post pockets and upon the side sills, said furring strips being cut away if necessary, as shown in Fig. 2, to pass over said side sills to 10 which they are bolted by means of the vertically extending bolts 25.

What I claim is:—

1. In a system of end framing, an end sill, side sills, post pockets connected with the 15 end sill near its middle and furring strips partly supported by said post pockets and an intermediate furring strip.

2. In a system of end framing, an end sill, side sills, post pockets connected with said 20 end sill near its middle portion, furring strips extending from said post pockets to the side sills and post pockets beyond said side sills.

3. In a system of end framing, an end sill, center girder, side sills, post pockets supported in a plane below the upper face of 25 said end sill near the ends thereof and intermediate its ends and relatively short furring strips resting on some of said post pockets and extending to said side sills.

30 4. In a car end framing, the combination comprising an end sill, longitudinal sills, post pockets abutting said end sill, posts resting in said pockets next said end sill, said posts extending below the upper plane of the end 35 sill, and relatively short furring strips resting on some of said post pockets and said longitudinal sills.

5. In a car end framing, the combination comprising an end sill, longitudinal sills, a 40 discontinuous furring strip resting on said longitudinal sills and post pockets connected with said end sill below the top plane thereof, said post pockets serving as additional supports for the furring.

45 6. In a car end framing, the combination comprising an end sill, longitudinal sills, a discontinuous furring strip resting on said longitudinal sills and post pockets having vertical flanges secured to said end sill and 50 lateral flanges serving as supporting means for said furring strips.

7. In a car end framing, the combination comprising an end sill, longitudinal sills, a 55 discontinuous furring strip resting on said longitudinal sills, end post pockets connected with said end sill below the top thereof so that said end sill serves as a closure for one side of said post pockets, said pockets comprising lateral flanges to aid in supporting 60 said furring, and end posts resting in said pockets.

8. In a car end framing, the combination comprising a flanged metal end sill, flanged 65 end post pockets secured thereto below the top plane of said sill, the sill forming a closure

for one side of said pockets and furring resting on the flanges of said end post pockets.

9. In a system of end framing, an end sill, a central girder, side sills, post pockets connected with the end sill near its middle, 70 furring strips partly supported by said post pockets and an intermediate furring strip supported above the central girder.

10. In a system of end framing, an end sill, side sills, post pockets connected with said 75 end sill near its middle portion, furring strips extending from said post pockets to the side sills and post pockets beyond said side sills, said post pockets resting behind the end sills.

11. In a system of end framing, an end sill, side sills, post pockets connected with said end/sill near its middle portion, furring strips extending from said post pockets to the side sills and post pockets beyond said side sills, said post pockets resting relatively lower 85 than the end sills.

12. In a system of end framing, an end sill, center girder, side sills, post pockets supported in a plane below the upper face of said 90 end sill near the ends thereof and intermediate its ends and relatively short furring strips resting on some of said post pockets and extending to said side sills, the end sill and side sills serving as side walls or closures for said pockets.

13. In a car end framing, the combination comprising an end sill, center sill, side sills, post pockets abutting said end sill and side sills, posts resting in said pockets next said end sill, said posts extending below the upper 100 plane of the end sill, and relatively short furring strips extending over parts of some of said post pockets and said longitudinal sills.

14. In a car end framing, the combination 105 comprising an end sill, longitudinal sills, a discontinuous furring strip resting on said longitudinal sills, post pockets connected with said end sill below the top plane thereof, said post pockets serving as additional 110 supports for the furring and corner post pockets secured to the webs of said side sills.

15. In a car end framing, the combination comprising an end sill, longitudinal sills, a 115 discontinuous furring strip resting on said longitudinal sills, end post pockets having vertical flanges secured to said end sill and lateral flanges serving as supporting means for said furring strips, and corner post pockets secured to the webs of said end sill and 120 side sills.

16. In a car end framing, the combination comprising an end sill, longitudinal sills, a 125 discontinuous furring strip resting on said longitudinal sills, end post pockets connected with said end sill below the top thereof so that said end sill serves as a closure for one side of said post pockets, said pockets comprising lateral flanges to aid in supporting said furring, end posts resting in said pock- 130

ets, and corner post pockets provided with lateral flanges adapted to support side nailing strips.

17. In a car end framing, the combination comprising a flanged metal end sill, flanged end post pockets secured thereto below the top plane of said sill, the sill forming a closure for one side of said pockets, furring resting on the flanges of said end post pockets, flanged

corner post pockets outside of the side sills, 10 secured thereto and to the end sill, and side nailing strips resting on said flanges.

In witness whereof I have hereunto set my hand in the presence of two witnesses.

ALLEN E. OSTRANDER.
